US0D1064711S

(12) **United States Design Patent** (10) Patent No.: **US D1,064,711 S**
(45) Date of Patent: ** Mar. 4, 2025

(54) **AIR FRYER LINER**

(71) Applicant: **Zhenwei Lin**, Guangdong (CN)

(72) Inventor: **Zhenwei Lin**, Guangdong (CN)

(**) Term: **15 Years**

(21) Appl. No.: **29/968,661**

(22) Filed: **Oct. 17, 2024**

(51) LOC (15) Cl. **07-01**

(52) U.S. Cl.

USPC **D7/354**; D7/388; D7/360

(58) **Field of Classification Search**

USPC D7/354, 359, 690, 388, 402–407, 360;
D23/370–376, 420; D32/53, 53.1

CPC A47J 37/01; A47J 37/0658; A47J 2202/00;
A47J 37/0885; A22C 15/008

See application file for complete search history.

(57) **CLAIM**

The ornamental design for an air fryer liner as shown and described.

DESCRIPTION

FIG. 1 is a top perspective view of my new design for an air fryer liner;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

1 Claim, 8 Drawing Sheets
